Specification for Design.

Patented Dec. 18, 1917.

Application filed January 2, 1917. Serial No. 140,316. Term of patent 3½ years.

To all whom it may concern:

Be it known that I, ANTHONY VAN GYTENBEEK, a citizen of the United States of America, residing at Paterson, in the county of Passaic, State of New Jersey, have invented a new, original, and ornamental Design for Display-Trays, of which the following is a specification, reference being had to the accompanying drawing, forming part thereof.

Figure 1, is a plan view of a display tray showing my new design.

Fig. 2, is a front elevation of the same.

I claim:

The ornamental design for a display tray, as shown.

In testimony whereof I have signed my name to this specification in the presence of two subscribing witnesses, this 27th day of December, 1916.

ANTHONY VAN GYTENBEEK.

Witnesses:

MARCELLA PLESSER,
HERBERT MOBERG.
